UNITED STATES PATENT OFFICE

138,023

DESIGN FOR A BUTTON

William L. Walker, Detroit, Mich.

Application October 18, 1943, Serial No. 111,417

Term of patent 14 years

(Cl. D17—2)

To all whom it may concern:

Be it known that I, William L. Walker, a citizen of the United States, residing at Detroit, in the county of Wayne, and State of Michigan have invented a new, original and ornamental design for Button, of which the following is a specification, reference being had to the accompanying drawing, forming a part thereof.

In the drawing:

Figure 1 is a top plan view of a button, showing my new design.

Fig. 2 is a transverse section thereof to show clearly the contour of the button top; and

Fig. 3 is a bottom plan view of the button.

The characteristic feature of the button is the relatively deep conical depression of the central portion of the button top at the bottom of which depression is a circular dome with a narrow flat margin corresponding to the flat margin bordering the outer edge of the button top.

I claim:

The ornamental design for a button, as shown and described.

WILLIAM L. WALKER.
